UNITED STATES PATENT OFFICE.

ALBERT A. EHRLICHMAN, OF MILWAUKEE, WISCONSIN.

ANTIGLARE ATTACHMENT.

Application filed May 12, 1926. Serial No. 108,555.

This invention relates to certain new and useful improvements in anti-glare attachments for head lights of the type commonly used on automotive vehicles and has as a 5 primary object the provision of improved means whereby all annoying or blinding rays of light are eliminated without loss of the effective road illuminating rays.

Numerous devices have been produced 10 having as their object the elimination of the blinding rays of light, but they are more or less objectionable in that the desired rays of light are destroyed and in addition they are expensive and cumbersome structures 15 protruding from the head light in such a manner as to be accumulators of foreign matter and thus soon become inoperative after a short period of use.

Having the above and other objectionable 20 features to the present type of anti-glare devices in mind, it is a further object of my invention to provide an improved device of the character described which is of very simple and efficient construction and which readily lends itself to application on all types 25 of head lights without requiring any change in the construction of the head light.

With the above and other objects in view 30 which will appear as the description proceeds, my invention resides in the novel construction, combination and arrangement of parts substantially as hereinafter described and more particularly defined by the appended claims, it being understood 35 that such changes in the precise embodiment of the herein disclosed invention may be made as come within the scope of the claims.

In the accompanying drawing, I have 40 illustrated one complete example of the physical embodiment of my invention constructed according to the best mode I have so far devised for the practical application of the principles thereof, and in which:

45 Figure 1 is a side view of a head light shown in conventional light lines and having my improved device attached thereto, the device being shown in vertical section, and

50 Figure 2 is a front elevation of my improved attachment, parts thereof being broken away and in section to more clearly illustrate structural details.

Referring now more particularly to the 55 accompanying drawing in which like nu-

merals designate like parts throughout the several views, the numeral 5 designates the housing or casing of a head light having a reflector 6 secured therein by a rim or other means 7 which preferably provides a 60 mounting for the usual glass front or lens 8. A lamp 9 is so located within the casing that its light is reflected forwardly through the lens 8.

The reflector 6 is, of necessity, concave in 65 shape and by reason of its contour throws the light in all directions, the lower half thereof throwing rays forwardly and upwardly which are very annoying to approaching vehicles and pedestrians, being 70 often-times so blinding as to obscure their vision. It is these rays that it is desired to control or eliminate and various means have heretofore been provided, such as blocking 75 off portions of the lens 8, or by putting shutters or the like thereon. This has been objectionable in that the desired rays of light are interfered with and the blinding rays still thrown forwardly and upwardly. My 80 improved device has been proven by actual test to throw the light forwardly on the road and sufficiently to the side as to cover the entire area without in anywise blinding or interfering with the vision of the driver of an approaching vehicle or a pedestrian.

85 My device consists of a cylindrical shell or casing 10 having its inner marginal edge flanged laterally, as at 11, to provide an attaching flange for engagement between the fastening ring 7 and the marginal edge 90 of the glass front or lens 8 from which it is preferably separated by a packing 11', the outer or forward marginal edge of the shell 10 being shaped, as at 12, to secure a glass front or lens 13 therein.

95 Extended horizontally across the shell at a point spaced an inch or more from the lowermost portion thereof is a strap or bridge member 14, the extreme ends of which are curved downwardly and inwardly, as at 15, to provide attaching tabs which are riveted or otherwise secured, as at 16, to the shell. 100 A series of approximately semi-circular deflecting or light baffling members 17 are located within the shell 10 and are secured in 105 place by having barbs or projections 18 formed on their ends and inserted through openings or slots in the strap 14 and then bent over, being soldered or welded in place, if desired, to afford added rigidity. Each 110

of the members 17 have different diameters and are struck from different radii, the smaller having its center near the lowermost portion of the shell 10 and the centers 5 being shifted upwardly as will be readily apparent upon inspection of Figure 2. The members 17 are all inclined inwardly and outwardly, being of approximately conical shape and the distance between the members 10 being substantially equal at their ends secured to the strap 14 but being increased from the small member to the larger member at their medial portions.

With the structure defined the rays of 15 light being thrown upwardly from the reflector 6 strike the members 7 and are either entirely eliminated or directed forwardly and downwardly onto the road if the members 7 are polished and the rays of light normally directed forwardly and downwardly by the reflector 6 are uninterfered with, extending forwardly onto the road with full strength. This is possible by reason of the angle of the members 17. As will be apparent, the outer-most member 17 has its medial portion spaced from the top of the shell a distance greater than the distance between the members 17 as the rays of light passing therebetween are inclined forwardly and 25 downwardly, and the disturbing rays of light being thrown between the strap 14 and the bottom of the shell 10 are entirely eliminated preferably by making that portion of the glass front 13 in a line therewith opaque, 30 as at 19. The opaque portion 19 may be made by directly coating the glass front or by attaching a name plate or the like thereover.

From the foregoing description taken in 40 connection with the accompanying drawing it will be readily apparent to those skilled in the art to which an invention of this character appertains that I have provided an improved anti-glare attachment which may be 45 applied to all types of head lights without necessitating any change in their construction, one in which the elements are protected

by glass on both sides and one which will be very efficient and practical.

What I claim as my invention is: 50

1. In a device of the character described, a shell adapted to be secured to a head light, a transverse support extending horizontally across the lower portion of the shell, and a plurality of nested curved members of different diameters having their ends secured to the transverse support, said curved members being of a width substantially equal to the width of the shell and having their walls inclined forwardly and downwardly, the 55 distance between adjacent members being gradually decreased from their central portions to their ends.

2. In a device of the character described, a shell adapted to be secured to a head light, 60 a transverse support extending horizontally across the lower portion of the shell, a plurality of nested curved members of different diameters having their ends secured to the transverse support, said curved members being of a width substantially equal to the width of the shell and having their walls inclined forwardly and downwardly, the 65 distance between adjacent members being gradually decreased from their central portions to their ends, and a glass front closing the 70 outer end of the shell.

3. In a device of the character described, the combination with a head light, a shell adapted to be fitted to the head light and 80 through which its rays of light extend, a transverse member extending horizontally across the shell at a point medially of its center and lowermost portion, a plurality of nested curved members of different diameters having their ends secured to the transverse member to receive support therefrom, and a glass closing the front of said shell, 85 the shell, transverse member and nested members being disposed within the circumference of the head light.

In testimony whereof I affix my signature.

ALBERT A. EHRLICHMAN.
